UNITED STATES PATENT OFFICE.

FRANK ALLEN, OF NEW YORK, N. Y., ASSIGNOR TO THE ALLEN ICE MACHINE COMPANY, OF SAME PLACE.

ABSORPTION REFRIGERATING-MACHINE.

SPECIFICATION forming part of Letters Patent No. 638,491, dated December 5, 1899.

Application filed July 29, 1899. Serial No. 725,451. (No model.)

To all whom it may concern:

Be it known that I, FRANK ALLEN, a citizen of the United States, residing in the city of New York, in the borough of Brooklyn and 5 State of New York, have invented certain new and useful Improvements in Absorption Refrigerating-Machines, of which the following is a specification.

This invention relates to certain improvements in absorption refrigerating-machines, for which Letters Patent of the United States were granted to me under date of June 28, 1898, No. 606,326, said improvements being designed for simplifying the construction of 10 the machine described in said Letters Patent for running the entire machine by exhaust-steam delivered from the different pumps used in connection with the machine, so that the use of live steam is entirely dispensed 15 with, and thereby a very economical working of the machine produced. This result of operating the refrigerating-machine solely by means of exhaust-steam can only be obtained by the absorption of the heat units of the hot 20 ammonia-gases as they are conducted from the generator to the condenser by the cold returning ammonia-water on the one hand and by the utilization of the cold obtained by the expansion of the liquid-ammonia by the weak 25 ammonia-water on the other hand, this equalization of the temperatures of the hot and cold 30 gases and liquids being carried on throughout the entire cycle, so that the very effective and economical running of the refrigerating- 35 machine is obtained.

My invention consists, therefore, of a refrigerating-machine in which the absorption of the expanding ammonia-gases by the weak absorption-water is accomplished by means 40 of a preliminary absorber and a final absorber, in connection with a gas-pump for facilitating the work of the absorbers, while the heating of the strong ammonia-water on its return to the generator is accomplished by 45 means of a primary equalizing coil, through the interior pipe of which the hot ammonia-vapors are conducted, a second equalizing-coil through the interior pipe of which the hot 50 weak ammonia-water coming from the generator is conducted, and finally by an exhaust-steam heater in which the exhaust-

steam from one or more of the operating-pumps of the machine is collected, as will be more fully described hereinafter, and finally pointed out in the claims.

In the accompanying drawings, Figure 1 represents a diagram showing in elevation the parts of my improved absorption refrigerating-machine. Fig. 2 is an elevation of that portion of the machine adjacent to the generator in which the strong ammonia-water returned from the absorber is gradually heated up in its course in the generator; and Fig. 3 is a perspective view of the expansion side of the machine, showing the preliminary and final absorber and its connection with the brine-cooler and liquid-ammonia receiver.

Similar letters of reference indicate corresponding parts.

Referring to the drawings, A represents the generator or still, which is charged with commercial aqua-ammonia. The generator is heated by a coil a, through which exhaust-steam from the engine of the circulating and ammonia pumps P is circulated, the heat of the exhaust-steam liberating the ammonia-vapors from the liquid. The pump P serves for conducting the strong ammonia-water from the absorber to the primary equalizing-coil, the exhaust-steam of its engine being supplied to the coil a of the generator, it being one of the pumps that is kept continuously running as long as the refrigerating-machine is in use and can supply, therefore, a uniform quantity of exhaust-steam to the generator. The generator is provided with an upright cylinder A', in which an equalizing-coil is arranged through which the strong ammonia-water is returned into the generator. The upright cylinder A' is connected at its bottom, as well as by branch pipes, with the horizontal portion of the generator. From the top of the upright cylinder A' of the generator A the hot ammonia-vapors liberated from the ammonia-water are conducted by a pipe a' to the interior pipe a² 95 of the primary equalizing-coil B, while the exterior pipe b serves for the passage of the strong ammonia-water that is returned from the absorber by the pump P. The strong ammonia-water having been cooled to a low temperature in the absorber is supplied from the pump P by the pipe b' to the upper end of the

exterior coil *b* and conducted in a counter-current to the hot ammonia-vapors through the primary equalizing-coil *B*. The hot ammonia-vapors are then conducted from the interior pipe *a*² by a pipe *a*³ to the upper end of a condenser *C*, which is cooled by means of cold water that is supplied by a spray-pipe above the condenser, as shown in Fig. 1. In the condenser *C* the ammonia-vapors are liquefied and conducted by a pipe *a*⁴, connected with the lower end of the condenser-coil, to the liquid-ammonia jar or receiver *L*, which is located, preferably, on the same floor or level with the generator. The hot ammonia-vapors are thus gradually cooled down to the point of liquefaction, first in their passage through the primary equalizing-coil and then in their passage through the condensing-coil. From the liquid-ammonia receiver *L* the liquid-ammonia is permitted to expand by means of two expansion-pipes *a*⁶ *a*⁷, which are each provided with a stop-cock, into the headers *E'* of a brine-cooler *E* and from the headers *E'* into two systems of expanding pipes that are surrounded by two systems of exterior pipes for the brine to be cooled. The brine-cooler *E* is composed of two sets of brine-cooling coils having headers at the lower and upper ends. To the lower headers the expanded ammonia-vapors are supplied, while the upper header *E*² is connected by a pipe *a*⁸ with the final absorber *H*. The upper ends of the interior coils of the brine-cooler *E* are connected with a header *E*³, which is connected by a pipe *e* with the brine-supply pump *P'*, the inlet-port of which is connected with a brine-tank *E*⁴ by a pipe *e'*. The brine-tank is located in any suitable position relatively to the refrigerating-machine proper. The lower ends of the interior brine-coils are connected with a header *E*⁵, as shown clearly in Fig. 3, and from this header the cold brine is conducted by a pipe *e*⁶ to the place of use.

The brine-cooler is preferably divided into two or more systems, each of which is composed of a number of individual coils. This is done for the purpose of producing a smaller or larger quantity of brine, according to requirements. In hot weather all the coil systems of the brine-cooler are used, while in cooler weather one-half the coils, or even a smaller number of the coils, of the same may be required for use.

The header *E*² at the upper end of the brine-cooler is connected by the pipe *a*⁸ with the lower end of the final absorber *H* and with the interior coil of the same, said interior coil being surrounded by an exterior coil through which the strong ammonia-water is conducted.

Above the final absorber is arranged a preliminary absorber *H'*, the lower header of which is connected with the upper header of the final absorber *H*, while its upper header is connected with the weak-ammonia-water cooler *F*. The weak-ammonia-water cooler *F* is connected in the same manner as the condenser *C* and supplied with cooling-water

by a spray-pipe above the same. The weak ammonia-water is forced by the pressure in the generator from the same through a pipe *f*, having a stop-cock *f*^x, and through the interior pipe of a secondary equalizing-coil *I*, while the exterior pipe of the coil *I* is connected at its upper end by a pipe *i* with the exterior pipe of the primary equalizing-coil *B*, as shown clearly in Figs. 1 and 2. The upper end of the interior pipe of the secondary equalizing-coil *I* is connected by a pipe *f'* with the lower end of the weak-ammonia-water cooler. The hot weak ammonia-water gradually gives out its heat to the strong ammonia-water, which is returned by the pump *P* from the absorber *H* and the receiver *R* for the strong ammonia-water, so as to heat the same preliminarily in its return to the generator. The weak ammonia-water passes then to the cooler *F*. It is then conducted from the upper end of the same by means of an injector *h* into the upper end of the preliminary absorber *H'*, the upper end of which is connected by a pipe *h'* with the interior pipe of the final absorber. As the weak ammonia-water is forced under a certain pressure into the upper end of the preliminary absorber *H'*, it carries along the cold ammonia-vapors, which are cooled in the coil of the preliminary absorber and absorbed by the weak ammonia-water in its passage through the preliminary absorber and conducted then into the final absorber, in the coils of which the final absorption of any unabsorbed vapors takes place at still lower temperature, so that the chilled strong ammonia-water is returned from the lower end of the final absorber *H* by the pipe *h*² into the strong-ammonia-water receiver *R*, then lifted by the pump to the primary equalizing-coil *B*, and conducted from the same to the secondary equalizing-coil *I*, as before described. From the lower end of the inner pipe of the coil *I* the strong ammonia-water is conducted by a pipe *i'*, connected with the inner pipe to a coil *m* at the interior of an exhaust-steam heater *M*, said exhaust-steam heater being connected with the exhaust-port of the steam-engine of the brine-pump *P'* or with any other pump of the machine, the outgoing pipe of the exhaust-steam coil being connected with the atmosphere. At the interior of the exhaust-steam heater *M* are arranged two coils *m* *m'*, one running in one direction and the other in the opposite direction, the upper end of the second coil being finally connected by a pipe *n* with a coil *m*² in the upright cylinder *A'* of the generator *A*, and then delivered to the lower horizontal part of the generator, as shown clearly in Fig. 1. The strong ammonia-water is heated in the coils of the exhaust-steam heater by the exhaust-steam which is supplied thereto, and still more in the upright cylinder of the generator by the contact of the hot ammonia-vapors with the equalizing-coils *m*² in the same, so that it is returned at a high temperature into the gen-

erator and in such condition that the ammonia-vapors can be quickly evaporated again by the heat of the exhaust-steam coil in the same, so as to be sent again through 5 the machine in the same continuous cycle as before described.

A gas-pump P^2 is connected with the pipe h' , by which the interior expanding pipe of the final absorber H is connected with the 10 upper end of the preliminary absorber H' . The pipe h' is provided with a stop-cock h^3 and connected by branch pipes h^4 and h^5 , respectively at each side of the stop-cock h^3 , with the inlet and outlet ports of the gas- 15 pump P^2 , as shown in Fig. 3. The exhaust-port of the steam-engine which operates the gas-pump is preferably connected with the exhaust-steam heater or the exhaust-steam is permitted to pass off into the atmosphere 20 in case the brine-pump supplies a sufficient quantity of exhaust-steam for the proper working of the generator. The gas-pump is started whenever in warmer weather the refrigerating-machine is to be run at its full 25 capacity, in which case the intermediate stop-cock h^3 is closed and connection made with the ports of the gas-pump P^2 by opening the stop-cocks of the pipes h^4 h^5 . When during 30 colder weather a smaller quantity of cold is to be supplied by the refrigerating-machine, the gas-pump is cut out by closing the stop-cocks in the pipes h^4 and h^5 and opening the intermediate stop-cock h^2 . By means of the gas-pump P^2 the refrigerating-machine can 35 be run at its full capacity whenever required by the outside temperature or at reduced capacity, the gas-pump forming, in connection with the sectional brine-cooler, a very effective means of regulating the capacity of the 40 refrigerating-machine and adapting it to the work required to be performed at different temperatures. The gas-pump also serves for drawing the expanded ammonia-gases through the outer pipes of the brine-cooler 45 and the interior pipe of the final absorber, so as to produce a lower pressure in said pipe and accelerate the motion to the ammonia-vapors through the pipes and the production of a lower degree of temperature.

50 It appears from the foregoing that the weak ammonia-water is cooled by two successive steps—first, by the cooling action of the secondary equalizing-coil I , and, secondly, by the action of the weak-ammonia-water cooler, 55 so as to be reduced in temperature preparatory to its reabsorption by the cooled expanded ammonia-vapors. This reabsorption takes place in the preliminary and final absorbers, the strong ammonia-water being delivered 60 from the latter at the low temperature of the expanding ammonia-vapors. This chilled strong ammonia-water is then during its return to the generator subjected to three successive heating actions—first, in the primary equalizing-coil B to the heating action 65 of the hot ammonia-vapors coming from the generator; secondly, in the secondary equal-

izing-coil to the action of the hot weak ammonia-water, and, lastly, in the exhaust-steam heater to the heat of the exhaust-steam 70 in the same, so that in this manner the heat of the hot ammonia-vapors of the weak ammonia-water and of the exhaust-steam of the different pumps is utilized for raising the temperature of the chilled strong ammonia- 75 water, while the low temperature of the expanding ammonia-gas is utilized for cooling the brine required and for producing the final absorption of the weak ammonia-water with the expanded ammonia-vapors, all these steps 80 together tending to great economy of fuel as compared with the absorption refrigerating-machines heretofore in use, in which the generators have been run by live steam.

Having thus described my invention, I 85 claim as new and desire to secure by Letters Patent—

1. The combination, with a generator, of a heating-coil within the same, a pump for returning the strong ammonia-water to the generator, a pipe connecting the heating-coil in the generator with the exhaust-port of one or more pump-engines, a primary equalizing-coil connected with the outlet-port of said pumps and composed of an interior coil for 90 the hot ammonia-vapors and an outer coil for 95 the strong ammonia-water, a secondary equalizing-coil, the outer coil of which is connected with the outer coil of the primary equalizing-coil and the interior coil of which is connected with the generator for conducting off 100 the weak ammonia-water, an exhaust-steam heater supplied with exhaust-steam, a coil in said exhaust-steam heater connected with the outer pipe of the secondary equalizing-coil, 105 and a pipe connecting the coil in the exhaust-steam heater with the generator for conducting the heated strong ammonia-water back to the generator, substantially as set forth.

2. The combination, with a preliminary absorber, of a cooler for the weak ammonia-water connected with said preliminary absorber, a final absorber composed of an outer and an interior coil, the outer coil being connected with the preliminary absorber while the interior coil is connected with the liquid-ammonia receiver for conducting the expanded ammonia-gases to the preliminary absorber, a pipe connecting the interior coil of the final absorber with the upper end of the preliminary absorber, a gas-pump, valved pipes connecting the suction and force ports of said pump with the pipe leading to the preliminary absorber connected with said connecting-pipe, and a stop-cock located in said connecting-pipe intermediately between the suction and force pipes of the gas-pump, substantially as set forth.

3. The combination, with a brine-cooler, consisting of a number of coils, each composed of an interior and an exterior pipe, of a brine-supply pump connected with the interior pipes of said coils, a liquid-ammonia receiver, pipes connecting said receiver with

the exterior pipes of the brine-cooler, a receiver for the strong ammonia-water, a final absorber composed of an exterior and an interior pipe, a pipe connecting the exterior 5 pipes of the brine-cooler with the interior pipes of the final absorber, a pipe connecting the lower end of the exterior pipe of the final absorber with the strong - ammonia - water receiver, a preliminary absorber connected with 10 the upper end of the exterior pipe of the final absorber, and a pipe connecting the interior coil of the final absorber with the upper end of the preliminary absorber so that the available cold of the expanded ammonia-vapors is 15 utilized in the final absorber for chilling the strong ammonia-water formed in the preliminary and final absorbers, substantially as set forth.

4. The combination, with a generator, of a 20 heating-coil, in the same, a circulating-pump, the exhaust-port of which is connected with the heating-coil, an outlet-pipe for the hot ammonia - vapors, a primary equalizing - coil comprising an interior coil for the hot ammonia-vapors and an exterior coil for the 25 strong ammonia-water, a condenser connected with the interior coil of said primary equalizing-coil, a secondary equalizing-coil comprising an interior coil for the weak ammonia- 30 water, and an exterior coil for the strong ammonia-water, a pipe connecting the generator

with the interior coil of the secondary equalizing-coil, a pipe connecting the exterior coil of the primary and secondary equalizing-coils, a cooler for the weak ammonia-water, connected with the interior coil of the secondary equalizer, a preliminary absorber connected with the weak-ammonia-water cooler, a final absorber comprising an interior coil and an exterior coil, the latter connected with the 40 lower end of the preliminary absorber, a pipe connecting the interior coil of the final absorber with the upper end of the preliminary absorber, a receiver for the liquid ammonia connected with the condenser, a receiver for 45 the strong ammonia-water connected with the lower end of the final absorber and with the primary equalizing-coil, a brine-cooler comprising an interior coil and an exterior coil, a brine-supply pump connected with the interior coil, pipes connecting the liquid-ammonia receiver with the exterior coils of the brine-cooler, and a pipe connecting the exterior coils of the brine-cooler with the interior coil of the final absorber, substantially as set forth. 50

In testimony that I claim the foregoing as my invention I have signed my name in presence of two subscribing witnesses.

FRANK ALLEN.
